(57) **CLAIM**

The ornamental design for a fender liner for a truck, as shown and described.

DESCRIPTION

FIG. 1 is a perspective view of a fender liner for a truck of my new design which is suitable for use on the left side of a truck cab;

FIG. 2 is a front view of FIG. 1;

FIG. 3 is a back view of FIG. 1;

FIG. 4 is a top view of FIG. 1;

FIG. 5 is a left side view of FIG. 1; and,

FIG. 6 is a right side view of FIG. 1.

The broken lines shown in FIGS. 3 and 6 are for illustrative purposes only and form no part of the claimed design.
